UNITED STATES PATENT OFFICE.

HORACE FURMAN, OF PETERSBURG, VIRGINIA.

STEAM-BOILER.

1,244,316.

Specification of Letters Patent. Patented Oct. 23, 1917.

Application filed May 8, 1917. Serial No. 167,286.

To all whom it may concern:

Be it known that I, HORACE FURMAN, a citizen of the United States, residing at Petersburg, R. F. D. #1, in the county of

5 Prince George and State of Virginia, have invented new and useful Improvements in Steam-Boilers, of which the following is a specification.

My present invention relates to improvements 10 in steam boilers, and more particularly to those of the type adapted for marine purposes. The primary object of the invention is to provide an improved boiler of this type whereby a maximum steaming capacity 15 with a given area of grate surface is obtained, the water passages being so arranged that proper circulation of the water is insured and the liberation of steam therefrom is facilitated. Another object of the 20 invention is to provide certain structural improvements in boilers of this type whereby the steaming capacity of the boiler may be determined by assembling an appropriate number of superposed units and the steaming 25 capacity may be increased or diminished by increasing or diminishing the number of units, the grate surface, however, remaining the same, and any unit may be easily and quickly removed for repair and replaced 30 and the water tubes of the units are supported at their inner and hottest ends by intermediate manifolds, thereby preventing sagging of the water tubes.

To these and other ends, the invention consists 35 in certain improvements, and combinations and arrangements of parts, all as will be hereinafter more fully described, the novel features being pointed out particularly in the claims at the end of the specification.

40 In the accompanying drawings:—

Figure 1 represents, partly in section and partly in front elevation, a marine boiler constructed in accordance with the present invention, the section being taken on the line 45 1—1 of Fig. 2; and

Fig. 2 is a view, partly in side elevation and partly in section, on the line 2—2 of Fig. 1.

Similar parts are designated by the same 50 reference characters in the several views.

The present invention is applicable generally to steam boilers of the water tube type. The invention, however, is particularly applicable to marine boilers, wherein 55 the space available for the boiler, and particularly the grate and combustion chamber,

is limited. The preferred embodiment of the boiler is shown in the accompanying drawings and will be hereinafter described in detail, but it is to be understood that 60 the invention is not restricted to the precise construction and arrangement shown, as equivalent constructions and arrangements are contemplated and will be included within 65 in the scope of the claims.

In the present instance, the boiler is provided with a grate 1 of suitable dimensions, a combustion chamber 2 having fire doors 3, and an ash-pit 4 is formed below the grate. The boiler proper comprises a set of upright manifolds 5, these upright manifolds being located at the outer corners of the boiler, upper and lower horizontal manifolds 6 which connect the upper and lower ends of the corner manifolds 5 at the front 70 and rear ends of the boiler, and horizontal manifolds 7 connect the upper and lower ends of the pairs of corner manifolds 5 at the respective sides of the boiler. The pair of corner manifolds 5 at each side of the 75 boiler is also connected by an appropriate number of intermediate horizontal manifolds 8, the number of these intermediate manifolds depending on the number of units composing the boiler. In addition to the upright corner manifolds 5, a pair of intermediate upright manifolds 9 is used, each of these intermediate upright manifolds connecting the horizontal upper and lower manifolds 6 at the front and rear, respectively, 80 of the boiler, and the intermediate upright manifolds 9 are connected by central horizontal manifolds 10 the number of which depends on the number of units composing the boiler. In the present instance, a pair of 85 steam-collecting drums 11 and 12 is used, each drum being connected at its ends to the upper horizontal manifolds 6 at opposite sides of the vertical center of the boiler by the fittings 13. Two sets of water tubes 90 14 and 15 are provided, these sets of water tubes being placed at opposite sides of the center manifolds 10. Each water tube comprises a unit and is in the form of return bends arranged horizontally. The water 100 tubes, according to the present invention, are carried by different sections of the boiler, which sections are assembled to provide a boiler of the desired capacity. In the present instance, the lowermost section is designated 110 A and it comprises the base member of the boiler composing the grate, combus-

tion chamber, ash-pit and the lower portion of the manifolds of the boiler; C designates the top section of the boiler, it comprising the steam-collecting drums, the tops of the manifolds of the boiler, and the uppermost water tubes of the boiler; and the intermediate section B comprises the intermediate portions of the manifolds and the intermediate water tube units. In order to 5 provide for this sectional construction of the boiler, the upright corner manifolds 5 are built up of sections of pipe detachably united by flange or other suitable fittings 16, the intermediate upright manifolds 9 being 10 similarly built up of sections detachably coupled or united to enable different numbers of sections to be used. In each instance, the sections A and C will be used and, in a boiler of minimum capacity, the section C 15 may be superposed directly on the lower or base section A, omitting the intermediate section B. In order to provide boilers of greater steaming capacity, one or more intermediate sections B are interposed between the base and top sections A and C. 20 As shown in the present instance, each section of the boiler comprises an outer horizontal manifold to supply water to the water tube units thereof, and a pair of center manifolds to receive the heated water containing steam from the water tube units. For instance, the water tube units of the base section are connected by the pipes 17 and 18 to the lower horizontal manifold 7, 25 and the inner ends 19 and 20 of these units are connected to the two lower central manifolds 10. The water tube units of the intermediate and top sections B and C are connected to receive water from the intermediate horizontal manifolds 8, and the inner 30 ends of the water tube of the intermediate section B and the inner ends of the lower water tube units of the top section C are connected to the central horizontal manifolds 10. Preferably, the upper water tube 35 units of the top section C are connected at their inner ends 21 directly to the bottom of the steam-collecting drum at the respective sides of the boiler. 40 By assembling the sections of the boiler in superposed relation and in numbers depending on the desired capacity of the boiler, the steaming capacity of the boiler is varied without, however, varying the area of the 45 grate surface, and the superposed relation of the sections insures maximum utilization of the heat from the combustion chamber before the gases or waste products of combustion reach the stack. By providing the 50 central or intermediate manifolds to collect the heated steam containing water from the water tube units, efficient circulation of the water through all the water tube units is insured, so that the generation of steam is 55 facilitated and damage to the water tube 60 units, due to inefficient or faulty circulation, is prevented.

Furthermore, these central or intermediate manifolds perform the additional function of mechanically supporting the inner 70 ends of the water tube units, thereby preventing sagging, such as occurs where water tube units extend entirely across the interior of the boiler.

Fittings 22 of any suitable type are employed to detachably connect the water tube units of each section whereby any one or more of these tubes may be removed or replaced without interrupting the service of the boiler, and also plugs 23 are provided 80 in line with the horizontal manifolds 7, 8 and 10 to permit cleaning of sediment from these manifolds without requiring dismantling of the boiler.

I claim as my invention:

1. A steam boiler comprising a steam drum, outer water manifolds, water tubes arranged in units at opposite sides of the vertical center of the boiler and connected at their outer ends to receive water from 90 said outer manifolds, intermediate water manifolds arranged between the outer manifolds and connected to the inner ends of the water tubes to receive water therefrom and to support the inner ends of the water tubes, 95 and risers for the outer and intermediate manifolds connected to one another and to the steam drum.

2. A steam boiler comprising a steam drum, horizontal outer manifolds, water 100 tube units arranged in vertical rows at opposite sides of the vertical center of the boiler, the units of each row being connected to receive water from the respective outer manifolds, central horizontal manifolds connected to the inner ends of the units of both rows, and vertical circulating pipes for the outer and central manifolds connected at their upper portions to one another and to the steam drum.

3. A steam boiler comprising horizontal outer water manifolds arranged at opposite sides of the boiler, vertical manifolds connecting them, vertical rows of water tube units, the units of each row being connected to the manifolds at the respective sides of the boiler, intermediate horizontal water manifolds connected to the inner ends of the water tube units, and vertical manifolds connecting said intermediate horizontal manifolds and connected at their upper ends to the vertical manifolds for the outer horizontal manifolds.

4. A steam boiler comprising a plurality of superposed sections, each section comprising an outer horizontal water manifold, water tube units connected to receive water from such units, an inner water manifold connected to receive water from such water tube units, and sectional vertical manifolds 125

having their upper ends connected to one another and connecting respectively the outer and inner manifolds.

5. A steam boiler comprising a plurality of superposed sections, each section comprising a pair of horizontal outer water manifolds, parts of vertical water manifolds, water tube units connected to receive water from the outer horizontal manifolds, inner 10 horizontal water manifolds arranged between the outer manifolds and connected to receive water from the water tube units, parts of vertical water manifolds connected to said intermediate horizontal manifolds, 15 and means connecting the upper ends of the vertical manifolds for the outer and inner horizontal manifolds.

6. A steam boiler comprising vertical water manifolds divided into sections, means 20 detachably connecting such sections, outer horizontal water manifolds connecting the

respective sections of the vertical manifolds, sets of water tube units connected to the respective horizontal manifolds to receive water therefrom, inner horizontal water 25 manifolds arranged between the outer horizontal manifolds and connected to the water tube units to receive water therefrom, vertical water manifolds divided into sections, the sections being connected to the respective inner horizontal manifolds, and means connecting the upper ends of the vertical manifolds for the outer and inner horizontal manifolds. 30

In testimony whereof I have hereunto set 35 my hand in presence of two subscribing witnesses.
